Term of patent 14 years

(Cl. D44—9)

FIG. 1

FIG. 2

FIG. 3

FIG. 4

FIG. 5

FIGURE 1 is a top plan view of a combined cup and saucer serving unit showing my new design;

FIGURE 2 is a front view thereof;

FIGURE 3 is a bottom view thereof;

FIGURE 4 is a rear view thereof;

FIGURE 5 is an enlarged scale cross-sectional view.

The essential features of the design are shown in full lines and reside primarily in the particularly configured cup and particularly configured saucer in inter-fitting relationship whereby a continuous line is defined by the vertical side of the cup and the concave top surface of the saucer.

I claim:

The ornamental design for a combined cup and saucer serving unit, substantially as shown and described.
